UNITED STATES PATENT OFFICE.

THOMAS J. JAMESON AND DORON ORLANDO LITTLE, OF WHEATLAND, CALIFORNIA.

ROTARY INTERNAL-COMBUSTION ENGINE.

1,189,115.

Specification of Letters Patent. Patented June 27, 1916.

Application filed December 6, 1915. Serial No. 65,313.

To all whom it may concern:

Be it known that we, THOMAS J. JAMESON and DORON ORLANDO LITTLE, citizens of the United States, residing at Wheatland, in the county of Yuba and State of California, have invented certain new and useful Improvements in Rotary Internal-Combustion Engines; and we do declare the following to be a full, clear, and exact description of the invention, such as will enable others skilled in the art to which it appertains to make and use the same.

Our invention relates to improvements in internal combustion engines, and more particularly to those of the rotary type.

The object of the invention is to provide a machine of the class described which although being of comparatively simple and inexpensive construction, will be highly efficient and durable and will possess a number of advantageous characteristics, novel provision being made for mounting the movable abutment and for preventing leakage from the combustion chamber around the rotor.

With the above general object in view, the invention resides in certain novel features of construction and in unique combinations of parts to be hereinafter fully described and claimed, the descriptive matter being supplemented by the accompanying drawings which constitute a part of this application, and in which:

Figure 1 is a central vertical longitudinal section through the improved engine with the rotors of the compressing and power cylinders shown in elevation; Fig. 2 is a vertical transverse section through the power cylinder and the parts therein; Fig. 3 is a detail section cut through the rotor within the power cylinder on a plane parallel to the axis thereof; Fig. 4 is a detail vertical section as viewed on the plane of the diametrically extending line 4-4 of Fig. 2; Fig. 5 is a vertical transverse section through the compressing cylinder and parts therein; and Fig. 6 is a detail sectional view taken on the plane designated by the line 6-6 of Fig. 5.

In describing the invention, reference

will be made to the accompanying drawings 50 by similar reference characters placed on corresponding parts throughout the several views. To this end, the numeral 1 designates a horizontal shaft rotatably mounted in appropriate bearings 2 and passing 55 through the compressing and power cylinders 3 and 4 respectively, both of such cylinders being shown as formed in sections and as being integrally joined together.

Keyed to the shaft 1 and disposed in the 60 power cylinder 4, is a power rotor 5 contacting with the curved wall of said cylinder and having in its periphery a depression 6 whose front end constitutes an abutment 7 coacting with a movable abutment 8 which 65 is pivotally mounted within the open inner side of a pocket 9 formed in the aforesaid curved wall of the cylinder 4.

The portions of the wall in question, on opposite sides of the pocket 9, are recessed 70 circumferentially at 10 throughout the width of such wall, these recesses receiving therein the opposite ends of an arcuate plate 11 which constitutes a packing shoe 75 against which the periphery of the rotor 5 travels. The plate 11 is provided with an open frame-like central portion received snugly in the pocket 9, whereby to hold said plate against shifting. The frame-like portion in question is preferably in the form 80 of a continuous flange 12 extending outwardly from the plate 11 and surrounding an opening 13 which is formed therethrough. It is within this opening 13 that the abutment 8 is free to swing, being pivotally 85 mounted upon a pin 14 passing through one of its ends and through the flange 12.

Preferably used in conjunction with the shoe plate 11, is a pair of set screws 15 threaded through the curved wall of the 90 cylinder 4 and bearing against coil springs 15' which exert their tension upon said plate, whereby as the latter wears it is forced inwardly to the necessary extent for retaining it at all times in close contact with 95 the periphery of the rotor 5.

By the features of construction described, it will be obvious that the plate 11 serves

not only as packing means, but as an efficient carrier for the abutment 8, this being therefore very simple yet desirable construction.

The pocket 9 is formed with an opening

- 5 16 for the reception of a spark plug, and with an intake 17 into which an intake pipe 18 discharges, such pipe leading from the compressing cylinder 3 and having therein a check valve 19 opening toward the pocket.
- 10 The curved wall of the cylinder 4, at a point spaced from the pocket 9, is formed with an appropriate exhaust port 20.

In order to effectively cool the engine, the rotor 5 is of hollow construction as shown most clearly in Figs. 2 and 3, being formed with an annular perforated partition 21, whereby it is divided into a pair of circular water receiving compartments 22 into which ports 23 formed longitudinally through the shaft 1, deliver. One of these ports is adapted to admit cool water into the rotor, while the other one conveys heated water therefrom, circulation being preferably created by an appropriate pump (not shown).

25 Within the compressing cylinder 3 and keyed to the shaft 1, is any preferred type of compressing rotor 25, such rotor being mounted eccentrically in the cylinder and contacting therewith at one point, at which 30 point a packing shoe 26 is disposed. The rotor 25 is shown as provided with a pocket 27 in its periphery, capable of receiving therein a runner 28 which is normally forced outwardly therefrom by a spring 29. As 35 shown most clearly in Fig. 6, the outer end of the runner is preferably equipped with a roller 30 to reduce friction.

Disposed to one side of the packing shoe 26, is an inlet port 31 leading from a carbureter or mixing valve, while positioned at 40 the other side of said shoe, is an outlet port 32 with which the pipe 18 communicates. It will thus be evident that as the shaft 1 is initially rotated, the runner 28 will draw 45 a charge of volatile mixture from the carbureter into the cylinder 3 and will then expel such charge through the pipe 18 to compress the same in the pocket 9. About this time, the abutment 9 moves into the recess 6 50 in the rotor 5, thus positioning the abutment 7 in advance of the pocket in question. By suitable timing means (not shown), an electric spark is now snapped in the aforesaid pocket, with the result that the charge of 55 volatile mixture therein is ignited, whereupon it expands and presses forwardly on the abutment 7, thus rotating the rotor 5 and starting the entire machine running under its own power. Needless to say, the 60 pressing cylinder 3 continually supplies the power cylinder 4 with explosive mixture, as long as the engine is in operation.

From the foregoing description, taken in connection with the accompanying drawings, it will be obvious that although the

construction of the engine is comparatively simple and inexpensive, we have provided a machine which will be efficient and durable.

In the drawings, certain specific details of construction have been shown for illustrative purposes, and in the preceding such details have been described, but obviously, numerous changes may be made, within the scope of the invention as claimed, without sacrificing any of the advantages thereof.

We claim:

1. A rotary engine comprising a cylinder having a pocket in the inner side of its curved wall, a packing shoe inset in a portion of said curved wall and having an opening communicating with the pocket, a pivotally mounted abutment movable into the opening in the shoe, a rotor in the cylinder having an abutment on its periphery, an exhaust port spaced from the pocket, and means for admitting pressure into said pocket. 70

2. A rotary engine comprising a cylinder having a pocket in the inner side of its curved wall, a packing shoe inset in a portion of said curved wall and having an opening communicating with the pocket, an abutment pivoted to the shoe and movable into the opening therein, a rotor in the cylinder having an abutment on its periphery, an exhaust port spaced from the pocket, and means for admitting pressure into said pocket. 90

3. A rotary engine comprising a cylinder having a pocket in the inner side of its curved wall, a packing shoe constituting a portion of said wall and having an open frame-like portion received snugly in the pocket, an abutment pivoted to swing into said open frame-like portion of the packing shoe, a rotor in the cylinder having an abutment on its periphery, an exhaust port spaced from the aforesaid pocket, and means for admitting pressure into said pocket. 100

4. A rotary engine comprising a cylinder having a pocket in the inner side of its curved wall, a packing shoe constituting a portion of said curved wall and having an opening registering with said pocket and a continuous flange projecting outwardly from the edge wall of said opening and received snugly in said pocket, an abutment pivoted to the flange to swing into the opening, a rotor in the cylinder having an abutment on its periphery, an exhaust port spaced from the aforesaid pocket, and means for admitting pressure into said pocket. 115

5. A rotary engine comprising a cylinder having a pocket in the inner side of its curved wall, said wall being recessed in a circumferential direction throughout its width in opposite directions from said pocket, an arcuate packing plate received in the recessed portions of the wall and having 125
